UNITED STATES PATENT OFFICE.

WILIE BLOUNT BRYAN, IRBY MORGAN MOORE, AND THOMAS MEADE, OF NEW YORK, N. Y.

DESIGN FOR A COUPON.

SPECIFICATION forming part of Design No. 23,397, dated June 26, 1894.

Application filed May 4, 1894. Serial No. 510,113. Term of patent 14 years.

To all whom it may concern:

Be it known that we, WILIE BLOUNT BRYAN, IRBY MORGAN MOORE, and THOMAS MEADE, all residents of New York, in the county of New York and State of New York, have invented and produced a new and original Design for a Coupon; and we do hereby declare that the following is a full, clear, and exact description of the invention, which will enable others skilled in the art to which it appertains to make and use the same, reference being had to the accompanying drawing, which forms a part of this specification.

The present invention relates to a new and improved design for a coupon, for that class of articles known as commercial coupon books, which coupons represent a certain value and are received as cash by tradesmen and others through arrangements made with the person or firm issuing the books.

The leading features of the design consist in a rectangular coupon having printed or otherwise produced thereon a series of horizontal wave lines, a circular figure near each corner, and a central rectangular figure, as illustrated in the accompanying drawing in which the figure represents a face view of the

coupon on a somewhat exaggerated scale, so as to more clearly illustrate the design.

Referring now to said drawing, the reference numeral 1 designates the coupon, which is of rectangular shape and has printed or otherwise produced on its surface, a number of horizontal wave lines, concentric with each other, or at equal distances apart throughout their length. Near each corner of the coupon is a circular figure marked 2 in the drawing and in the center is a rectangular figure 3. These figures taken in connection with the wave lines and their relative positions form a very attractive and ornamental coupon.

What we claim is—

The design for a coupon herein shown and described.

In testimony that we claim the foregoing as our own we have hereunto affixed our signatures in presence of two witnesses.

WILIE BLOUNT BRYAN.
IRBY MORGAN MOORE.
THOMAS MEADE.
